Letters Patent No. 236. Dated Oct 9. 1849.

.....

The schedule referred to in these letters Patent and
making part of the same.

To all whom it may concern: Be it known that I
G. W. Chambers, of Troy, in the County of Rensselaer, and
State of New York, have invented or produced a new
design of Parlor Stone Plate, which I call the "Clinton
Parlor St. P." and I do hereby declare that the follow-
ing is a full clear and exact description of the same
reference being had to the annexed drawing making
a part of this specification.

In the drawing I have represented only a part of the
stone plate, the remainder being a repetition of and
corresponding with that represented on other parts
of the plate as is plainly to be seen by reference to
the drawing.

What I claim as new and desire to secure by letters
